(57) **CLAIM**

The ornamental design for a combination of key buttons for a handset, as shown and described.

DESCRIPTION

FIG. 1 is a front view of a combination of key buttons for a handset showing our new design; and,

FIG. 2 is a perspective front view thereof.

The broken line showing of environmental structures is for illustrative purposes only and forms no part of the claimed design.

1 Claim, 2 Drawing Sheets

FIG. 1

FIG. 2
